PAINT BRUSH SUPPORT

George Rosenberger, Muncie, Ind.

Application June 21, 1938, Serial No. 215,046

4 Claims. (Cl. 248—110)

In connection with the work of paper hanging, wherein the liquid paste therefor is contained in a sizable receptacle such as a bucket of conventional size, usually about twelve inches in diameter, there has long been inconvenience to the worker, incident to the difficulty of the finding or the providing of a suitable object upon which to dispose the paste brush from time to time during its employment in the applying of the paste to the lengths, one after another, of the wall paper.

It being desirable that the brush, during the intervals when it is not actually in hand, should be in a given and convenient location and as closely adjacent as possible to the paste supply, my invention has proceeded upon the concept of providing a support device which is capable of being attached to the bucket. In carrying out my idea, the object of the invention is to provide a device which is adapted to be readily attached to, and as readily detached from the bucket, and which said device in the attached position will constitute a practicable support upon which the paste laden portion of the brush may be reposed; such device being light in weight, economical of manufacture, durable, capable of being easily cleaned, and which will occupy relatively small space when not in use.

My invention is illustrated in the accompanying drawing, and it is described in the following specification, and defined in the appended claims.

In the drawing—

Figure 1 is a view of my improved support device for paste brushes and the like, such device being of form and proportions as applicable to a bucket of conventional size and shape.

Figure 2 is a view taken in the direction of arrow 2 in Figure 1.

Figure 3 shows the appearance of the invention installed, a portion of the upper part of the bucket being broken away.

Figure 4 is a top plan view taken in the direction of arrow 4 in Figure 3, in this view the position of the brush in the supported position being indicated by broken lines.

Figure 5 is a side view taken in the direction of arrow 5 in Figure 3, in this view the position of the brush in the supported position being indicated by broken lines.

Figure 6 is a view illustrating a modification to which it lends itself whereby it may be adapted to support an object other than and in addition to the brush, such as for example, a cake of soap, or cloth, or relatively small implement.

Figure 7 is an end view taken in the direction of arrow 7 in Figure 6.

My invention, in its present embodiment, and which is intended for use in connection with a bucket of conventional size, consists of a metal plate, preferably of sheet steel or sheet iron of about number twenty-two gauge, and which is about twelve and one-half inches in length and is of width in proportion. At a location spaced from each end of this plate A, is provided an inclined slot B which extends from the bottom edge of the plate to a point relatively near the top edge of the plate.

The portions of the ends of the plate made free by said slots, are designated as tangs C and C. The widened upper end of each of said slots may be designated as an eye D and in which is to be received the rim R of the bucket when the plate will have been placed in the installed position, as shown in Figures 3, 4 and 5 of the drawing. The upper part of the said plate, in the portion thereof intermediate the zone of said slots, is cut away to a plane which is below the plane of the eyes D and D of the said slots, there being thus constituted a resting surface or seat F and the opposed upright cheeks G and G. The corners H and the corners K of the bottom of the tangs and the bottom of the body portion of the plate, respectively, at the bottom of the slots, are slightly rounded.

The manufacturing of this article involves simply the stamping of same by dies suitably provided therefor, and the smoothing of the edges. Being flat, it lends itself to extreme economy and convenience in finishing, as by painting, enameling or plating; and to economy and facility in the handling thereof in merchandising. Its surfaces being unobstructed and regular there is suitable area upon which instructive or advertising matter may be applied.

Obviously the device is capable of being embodied in modified forms, and for receptacles of various sizes and having rims of plain or beaded formation. Accordingly it will be understood that the invention is not limited to the precise construction and conformation as illustrated in this typical presentation.

Placing the invention in the attached position consists simply in the disposing of the plate with its corners K and K at engagement with the inner face of the rim of the bucket, the corners H and H of the tangs being upon the outside of said rim. In the act of pressing downwardly on the plate, the tangs in their impingement against the exterior surfaces of the bucket, come to repose in alignment offset from the alignment of the body portion of the said plate upon the in-

terior of the bucket, and in a direction toward the plane of the vertical axis of the bucket. At the same time, the body portion of the plate will have come to repose directly against the interior 5 face of the bucket wall and is in position vertical or slightly inclined toward the wall of the bucket. Thus the plate in its installed position, as shown in Figures 3, 4 and 5, is in firmly attached position, its body portion having assumed the curvate 10 formation as shown in Figure 4. The resting seat F being at a plane below the plane of the top of the bucket, the brush, as indicated by the broken lines, is so retained, that such drip as there may be is within the confines of the bucket.

15 Projecting of the brush beyond the rim of the bucket is prevented, and the cheeks G and G prevent the brush from being shifted sidewise. The resting seat and cheeks also constitute suitable edges against which the worker may impinge the brush when working the paste content out of it.

20 Detaching the device from its operative position, consists simply in grasping same and pulling it upwardly, the tangs yielding sufficiently that the plate is readily drawn clear from its 25 attached position and whereupon it returns to the flat status as illustrated in Figure 1. It is easy to clean, and it may readily be handled and utilized along with the implements generally forming part of the kit of the worker.

25 30 Whereas the invention is referred to as being especially desirable for the use of the artisan handling the brush wherein the use of paste is involved, it will be understood that the invention is equally useful to a person handling a brush laden with any kind of liquid material such as kalsomine or paint. Also the invention is useful where the work of washing is to be done and wherein a bar of soap, or a small brush, or cloths, 35 or other implement is needful. In this event

there may be recommended a modification consisting of transverse slicing of the lower portion of the body of the plate, thereby providing tongues L and L which are adapted to be bent at a right angle position, and in which they constitute horizontal rests, as shown by the broken lines in Figure 7.

5 What I claim as my invention, is:

1. A support device adapted to be attached to a receptacle of the kind described, consisting of 10 a resilient plate, each end of which is provided with a slot which extends from the bottom edge of the plate diagonally to near the top of the end portion of the plate, the said slots being divergent.

15 2. A support device adapted to be attached to a receptacle of the kind described, consisting of a resilient plate, each end of which is provided with a slot which extends from the bottom edge of the plate diagonally to near the top edge of 20 the end of the plate, the said slots being divergent, and each being of increased width at its upper end.

25 3. An attachment for a bucket, consisting of a rectangular springy plate having spaced similar diverging slots extending from the bottom edge of the plate and to near the top edge thereof, and each being of increased width at its upper end.

30 4. An attachment of the kind described, consisting of a rectangular resilient metal plate having spaced diverging slots extending from the bottom edge of the plate to near the top edge thereof, and the upper part of the plate in the intermediate portion thereof being recessed to a 35 plane below the plane of the top ends of the said slots.

GEORGE ROSENBERGER.
